UNITED STATES PATENT OFFICE.

HARRY RALPH RICARDO, OF LONDON, ENGLAND.

PISTON FOR INTERNAL-COMBUSTION ENGINES.

1,377,438.

Specification of Letters Patent.

Patented May 10, 1921.

Application filed December 10, 1920. Serial No. 429,729.

To all whom it may concern:

Be it known that I, HARRY RALPH RICARDO, subject of the King of England, residing at London, in England, have invented certain new and useful Improvements in Pistons for Internal-Combustion Engines, of which the following is a specification.

This invention relates to pistons for internal combustion engines and has for its object to effect certain improvements in the pistons covered by the present inventor's U. S. patent application Ser. No. 77640 filed 11/2/16, Patents Nos. 1346845 and 1294833, and patent application Ser. No. 230854 filed 23/4/18.

According to this invention the piston head which is constructed of aluminium or aluminium alloy comprises a flanged disk 20 with a hollow projection of less diameter than the disk which is formed integral with and projects from one face thereof. Bosses adapted to carry the gudgeon pin are formed at or near the end or at some intermediate 25 point in the length of the projection. A part which is formed of cast iron or the like and performs guiding functions and has substantially the same diameter as the piston head comprises two oppositely 30 placed slipper members which lie on either side of the gudgeon pin and are formed integral with and connected together by one or more relatively narrow rings. One of these rings is formed so as to fit 35 on to and engage the hollow projection to which it is connected by studs or bolts. Preferably the hollow projection has formed at or near its end enlargements which constitute the bosses adapted to carry the gudgeon 40 pin and a thickened annular part or flange. In this case the two slipper members are connected about the center of their lengths by a relatively narrow ring which is formed integral with the slippers and the 45 inside of this ring is adapted to engage the thickened part or flange at the end of the hollow projection. On the ring which connects the slipper members and between the latter are lugs or lips which project so as 50 to lie opposite to the ends of the gudgeon pin and retain this pin in the bosses. In the case where the slippers are connected by two rings one of these rings is disposed about the center of the lengths of the slip- 55 pers while the other ring is formed at the outer end of these slippers and provided

with an inwardly directed flange adapted to but up against and be connected to the flange or thickened part at the end of a portion of the hollow projection which extends beyond 60 the gudgeon pin bosses. In either case when the guide portion is in place the plane of the gudgeon pin axis cuts the slipper members at or about the center of their lengths and those edges of the slippers which lie nearest 65 to the flange on the head of the piston are so positioned that there is a space between the edge of the flange and the adjacent edges of the slippers.

The invention may be carried out in practice in various ways but the accompanying drawings illustrate two alternative constructions that may be adopted. In these drawings—

Figure 1 is a side elevation of one form of 75 the improved piston.

Fig. 2 is a longitudinal section in the plane of the gudgeon pin axis.

Fig. 3 is a longitudinal section on the line 3—3 of Fig. 2 the section being taken transversely to the gudgeon pin.

Fig. 4 is a transverse section on the line 4—4 of Fig. 1 looking in the direction of the arrows.

Fig. 5 is a side elevation of a modified 85 construction.

Fig. 6 is a longitudinal section on the line 6—6 in Fig. 5 looking in the direction of the arrows, the section lying in the plane of the 90 gudgeon pin axis.

Fig. 7 is a longitudinal section transverse to the gudgeon pin and on the line 7—7 of Fig. 6.

Fig. 8 is a transverse section on the line 8—8 of Fig. 5 looking in the direction of the 95 arrows.

Like letters indicate like parts throughout the drawings.

Referring to the construction shown in Figs. 1 to 4 inclusive, the piston head comprises a solid disk A having either a flat or dished face and a peripheral flange A' of suitable width grooved to carry piston rings or other suitable packing means. A hollow projection B which is substantially rectangular as shown in Fig. 4, or may have such other cross section as for example approximately cylindrical as may be desired, extends from the underside of the head disk A with which this hollow projection is 105 formed integral. At the outer end of the hollow projection B and on opposite sides 110

thereof are bosses C of suitable formation adapted to carry the gudgeon pin D and at the side of these bosses adjacent to the piston head is a thickened annulus E forming a 5 flange which extends around the projection B between the bosses C.

The guide portion of the piston comprises two separated slipper members F and F' the shape and dimensions of which may be 10 either similar or, as in the case illustrated, the bearing area of the one slipper F is somewhat greater than that of the other F'. A ring G having an outwardly directed flange G' extends between and is formed 15 integral with the slippers F F' and serves to connect them together. The width of the ring G is relatively small and considerably less than the length of the slippers while the outer edge of the flange G' unites 20 with and runs across the inner faces of the slippers the whole ring thus lying within the slippers. If desired webs in suitable number and dimensions may be provided within the slippers and extending from 25 them to the ring G G'. This ring fits on to the end of the hollow projection B so that the flange E rests against the face of the flange G' while the main portion G of the ring slides over and engages the end 30 of the hollow projection. Between the slippers the ring extends across the ends of the gudgeon pin D as shown in Figs. 1 and 2. The flange G' is connected to the flange E by studs or bolts H which pass 35 through bosses E' and G² formed respectively at intervals around the flange E and the ring G. The formation of these engaging parts is such that expansion of the end of the hollow projection B within the 40 slipper ring G G' will not cause distortion of this ring and of the slippers. If desired the end of the projection may be chamfered off where it lies within the slipper ring.

As mentioned the piston head A with its 45 flange A' and the projection B are all formed integral of aluminium or aluminium alloy while the guide portion comprising the two slippers F F' and the ring G G' which is integral with the slippers and connects them is preferably constructed of a metal having a substantially lower coefficient of expansion than the aluminium head portion such as cast iron or the like.

Referring to the alternative construction 50 shown in Figs. 5 to 8 inclusive, it will be seen that in this case the connection between the hollow projection B and the ring which joins the slippers F F' is disposed at the end of the hollow projection beyond 55 the gudgeon pin bosses. The hollow projection is somewhat shorter than in the construction shown in Figs. 1 to 4 and the gudgeon pin D is positioned nearer to the head A of the piston, but still lies 60 wholly within the length of the slippers so

as to bring the cylinder wall reaction with in the slipper surface in contact with the cylinder wall.

In this modified form the gudgeon pin bosses C are formed at the end of the hollow projection B which again has a substantially rectangular form in cross section as shown in Fig. 8. The annular flange E is developed from and extends between the gudgeon pin bosses C at the end of the 70 hollow part B. The ring which lies within and is connected to the slippers F and F' in this case comprises an annular part G connected to the slippers by a flange G', the part G also having an inwardly directed flange G³ adapted to butt up against the face of the flange E. The part G lies around the periphery of the flange E. The flanges G³ and E are connected together by 75 studs or bolts H. Webs F² extend in the longitudinal direction from the inner sides of the slippers F and F' to the ring G G'. 80

On that edge of the ring G which faces the head A and on each part of the ring which extends between the slippers F and F' there is formed a lip or lug G⁴ which projects from the edge of the ring toward the head of the piston. Each of these lugs G⁴ is of such dimensions that it will lie opposite to one end of the gudgeon pin D 90 and overlap this end either partially as shown or entirely. These lips G⁴ thus serve to keep the gudgeon pin in place.

In either case the detailed formation of the parts may vary as found desirable as 100 for example the construction, shape and dimensions of the slippers F F' and of the ring which is formed integral with them and serves to connect them to the hollow projection B. In all cases, however, the 105 length of the slippers will be such as to bring the line of cylinder reaction due to the connecting rod thrust within the surface of the slipper in contact with the cylinder wall. The arrangement of the 110 webs F² if employed within the slippers may also be varied. Perforations are conveniently formed in the slippers as shown.

What I claim as my invention and desire to secure by Letters Patent is:—

1. A piston for an internal combustion engine comprising a flanged disk constituting the head with a hollow projection of less diameter than the disk formed integral with this disk and projecting from one face thereof of this projection carrying bosses adapted to receive the gudgeon pin and the said bosses being disposed toward the end of the projection remote from the head all these parts being constructed of aluminium or aluminium alloy, in combination with a part formed of material such as cast iron which performs guiding functions and has substantially the same diameter as the flanged piston head this guide part comprising two oppositely 115 120 125 130

placed slipper members which lie on either side of the gudgeon pin and are formed integral with and connected together by relatively narrow members which are operative to retain the gudgeon pin in place, and means for connecting the slipper member to the hollow projection as set forth.

2. In a piston for an internal combustion engine the combination of a flanged disk 10 constituting the piston head, a hollow projection of less diameter than the disk which is formed integral with this disk and projects from one face thereof, bosses adapted to carry the gudgeon pin formed on the hollow projection and disposed toward the end thereof which is remote from the disk, a pair of oppositely disposed slipper members forming a guide which has substantially the same diameter as the piston head, these 15 slipper members being integral with and connected together by relatively narrow members which are respectively operative to keep the gudgeon pin in place, and means for connecting the slipper guide part to the hollow projection as set forth.

3. A piston for an internal combustion engine comprising a flanged disk constituting the head with a hollow projection of less diameter than the disk formed integral with this disk and projecting from one face thereof, this projection carrying bosses adapted to receive the gudgeon pin and the said bosses being disposed toward the end of the projection remote from the head, all these 25 parts being constructed of aluminium or aluminium alloy, in combination with a part formed of material such as cast iron which performs guiding functions and has substantially the same diameter as the 30 flanged piston head, this guide part comprising two oppositely placed slipper members which lie on either side of the gudgeon pin and are formed integral with and connected together by a relatively narrow annular member, those parts of this member which 35 lie between the slippers being operative to retain the gudgeon pin in place, and means for connecting the slipper member to the hollow projection as set forth.

4. In a piston for an internal combustion engine the combination of a flanged disk constituting the piston head, a hollow projection of less diameter than the disk which is formed integral with the disk and projects from one face thereof, bosses adapted to 50 carry the gudgeon pin formed on the hollow projection and disposed toward the end thereof which is remote from the disk, a

relatively narrow annular member, a pair of slipper members formed integral with 55 the annular member and oppositely disposed thereon, these slipper members constituting a guide which has substantially the same diameter as the piston head, and means for connecting the annular member to the hollow projection so that the annular member is operative to keep the gudgeon pin in place.

5. In a piston for an internal combustion engine the combination of a flanged disk 70 constituting the piston head, a hollow projection of less diameter than the disk which is formed integral with this disk and projects from one face thereof, bosses adapted to carry the gudgeon pin formed on the hollow projection and disposed toward the end thereof which is remote from the disk, an annular enlargement formed on the hollow projection in the neighborhood of the bosses, an annular member adapted to fit 75 onto the hollow projection and engage the annular enlargement thereon and also lie across the ends of the gudgeon pin and keep it in place, a pair of slipper members formed integral with the annular member 80 and oppositely disposed thereon, these slipper members constituting a guide which has substantially the same diameter as the piston head, and means for connecting the annular slipper-carrying member to the 85 hollow projection as set forth.

6. In a piston for an internal combustion engine the combination of a flanged disk constituting the piston head, a hollow projection of less diameter than the disk which is formed integral with the disk and projects from one face thereof, bosses adapted to carry the gudgeon pin formed on the hollow projection and disposed toward the end thereof which is remote from the disk, 100 an annular member having a cylindrical part and a flanged part and adapted to fit onto and engage the hollow projection so that parts of this member will lie across the ends of the gudgeon pin and keep it in 105 place, a pair of slipper members mounted on and formed integral with the annular member and oppositely disposed, these slippers forming a guide which has substantially the same diameter as the piston head, and means 110 for connecting the annular slipper-carrying member to the hollow projection as set forth.

In testimony whereof I have signed my name to this specification.

HARRY RALPH RICARDO
